(57) **CLAIM**

The ornamental design for the flexible container, as shown.

DESCRIPTION

FIG. 1 is a right-front, perspective view of the flexible container showing my new design;

FIG. 2 is a rear elevation view thereof;

FIG. 3 is right-side elevation view of my new design, the left-side elevation view being identical thereto;

FIG. 4 is the top view of my new design; and,

FIG. 5 is the bottom view of my new design.

The broken line showing of the environment is for illustrative purposes only and forms no part of the claimed design.

UNITED STATES PATENT AND TRADEMARK OFFICE
CERTIFICATE OF CORRECTION

PATENT NO. : Des. 505,066 S
APPLICATION NO. : 29/174913
DATED : May 17, 2005
INVENTOR(S) : Ootubo

Page 1 of 4

It is certified that error appears in the above-identified patent and that said Letters Patent is hereby corrected as shown below:

Delete Title page illustrating a figure(s), and substitute therefor, new Title page illustrating a figure(s). (attached)

Delete drawing sheet 1-2, and substitute therefor drawing sheet 1-2. (attached)

Signed and Sealed this

Twenty-eighth Day of August, 2007

A handwritten signature in black ink, appearing to read "Jon W. Dudas". The signature is written in a cursive style with a large, stylized "J" and "W".

JON W. DUDAS
Director of the United States Patent and Trademark Office
